UNITED STATES PATENT OFFICE.

FELIX SPINDEL, OF MORRISVILLE, PENNSYLVANIA.

RUBBER-STOCK RACK.

Application filed January 15, 1925. Serial No. 2,709.

This invention relates to racks and particularly to an improved rack for rubber stock and has for an object to provide a construction wherein the stock may be quickly and easily inserted and removed.

Another object of the invention is to provide a rack for rubber stock wherein the parts are so formed that the stock may be quickly inserted in the rack directly from the mill.

A still further object of the invention is to provide an improved rack which will receive the hot rubber stock from the mill and will properly support the same without the use of soapstone.

In the accompanying drawings—

Figure 1 is a sectional view through Figure 2, approximately on line 1—1.

Figure 2 is a side view of a rack, disclosing an embodiment of the invention.

Figure 3 is a sectional view through Figure 2, approximately on line 3—3.

Figure 4 is a top plan view of a bracket showing certain features of the invention.

Figure 5 is a perspective view of the frame supporting one of the perforated plates illustrated in Figure 1.

Referring to the accompanying drawing by numerals, 1 indicates a frame which may be of any suitable construction, preferably formed of four angle iron posts 2 with connecting angle iron braces 3 at the top and bottom. Preferably, there is no angle iron brace 3 across the top at the front, though there is one across the bottom at the front.

The posts 2 at the rear are provided with apertures for receiving the respective bolts 4 extending through the turned down ends 5 of the rear bar 6 of the plate supporting frame 7. This frame is provided with a front bar 8 and side bars 9 and 10. A plate 11 is riveted or otherwise secured to this frame and entirely covers the same, said plate being comparatively thin and perforated.

The frame 7 is of comparatively thick strips of metal while the plate 11 is comparatively thin but acts as a proper support for a load of rubber which may be mounted thereon. At the front, the frame 7 is provided with supporting feet 12 which rest on the next lower plate 11 while the feet 12 of the bottom frame rest on the front angle bar 3. It will be noted also that the lowermost frame 7 is provided with side angle bars 13 to which the respective ropes 14 and 15 are connected. In constructing

the frame, the various supporting legs are so formed that in raising they prevent the frame from jumping and chattering. Also, in case it is desired to lower all the plates 60 at one time, this construction of legs prevents the respective succeeding plates catching the next plate.

As indicated in Figure 1, the various frames 7 are pivotally connected to the rear post 2 and normally remain in a horizontal position though they are adapted to be elevated as shown in the upper part of Figure 1 preparatory to being loaded. The ropes or cables 14 and 15 are connected with suitable drums 16 and 17 which are rigidly secured to a shaft 18 and said shaft is provided with a removable crank 19 whereby the cables may be wound on the drums at any time.

In use, the rack 20 is raised or run up to the top which trips all of the catches 21 and holds them out of the way as it continually bears against the same. In order to prevent the rack from moving downwardly again, the pawl 23 is caused to function which locks the parts against downward movement until manually released. After the rack has been thus raised, all of the plates 11 may then be raised to an almost vertical position by rotating the crank 19. Upon the rotation of this crank, shaft 18 will be rotated and in turn the respective drums 16 and 17 whereupon the cables 14 and 15 will be wound on the drums and the plates swung to their upper position. As soon as the plates have all been swung to their upper position, the pawl 23 is moved manually to an inoperative position while the crank 19 is being held stationary. The 85 rack 20 is then quickly lowered whereupon the various catches 21 will immediately swing into operative position. When this has been done, the crank 19 may be released. To release the various plates 11 one at a time, the catch or pawl 23 is moved to an operative position as shown in Figure 1 and then the crank 25 rotated sufficiently to elevate the rack 20 the proper distance for striking the lowermost catch 21 and swinging the same to a disengaged position whereupon the lowermost plate 11 will swing by gravity to a horizontal position. This action is repeated for each plate and may be done as rapidly as desired. Usually one 100 plate is released and allowed to drop to horizontal position, after which, it is loaded with

50

rubber and then a second plate dropped into position and loaded. This action is continued until all or as many of the plates are dropped as desired. In loading the rack, 5 the rubber is preferably placed so as to project a short distance beyond the front edge whereupon in emptying the rack it is only necessary to grasp each piece of rubber and pull the same from the rack. To load the 10 rack again, the same operation is repeated. In order that the rack 20 shall be limited in its downward movement, the guiding bar 28 is provided with an offset or turned over end 28' at the bottom which acts as an abutment for limiting the downward movement 15 of the rack.

From Figure 2 it will be noted that the shaft 24 is rigidly secured to the pinion 22 and extends to the front of the machine 20 where a crank 25 is secured thereto. Connected by rivets or other means with the rack 20 are guiding loops 26 and 27 which loosely fit around the vertical guiding bar 28 rigidly secured by a bolt or other means 25 at 29 to one of the bars 3 at the bottom of the machine to a brace 3' near the center and to a bracket 30 at the top of the machine by a suitable bolt or rivet. The bracket 30 is substantially U-shaped and is 30 bolted or otherwise rigidly secured to the angle bar 31, which angle bar is riveted or bolted to the brace 3' and also to the top members 3. Mounted on one face of the angle bar 31 are a number of catches 21 35 which are pivotally mounted on the angle bar by suitable pins 32. These catches are merely short sections of a flat bar and provided with a weight 33 at one end and a beveled portion 34 at the opposite end. 40 When the rack 20 is moved upwardly, the rear part of the rack bar will engage one end of the catches 21 and swing the catches to a substantially vertical position. After the cables 14 and 15 have swung all of the plates 45 11 to a substantially vertical position, they are held temporarily in that position by the cables and rack 20 is then actuated until it is moved to its extreme down position whereupon all of the catches 21 are released 50 and will automatically swing to a position whereby one catch will be in front of each of the frames 7. This will hold all of the frames in their elevated position and when it is desired to use the first frame and plate, 55 rack 20 is moved upwardly until the first catch is swung to a vertical position whereupon the lowermost frame and its plate will automatically fall to a substantially horizontal position. A load of rubber is placed 60 on this plate and then rack 20 is again elevated a short distance or until the next catch 21 has been released whereupon the second plate 11 from the bottom will be released 65 and will automatically drop to a horizontal position. A load of rubber is placed on

this second plate or sheet 11 and a third plate is allowed to drop. This action is continued until the rack is entirely loaded or until a desired quantity has been provided. When the rack 20 is being lowered it is, of course, necessary to manually move pawl 23 out of engagement with the pinion 22 but the pawl remains in engagement with the pinion as the rack is slowly moved upwardly for causing a release of the various 75 plates 11. By elevating the plates as shown in Figure 1, the rubber stock, which is usually hot, may be quickly thrown into position and also readily removed as each piece of rubber is allowed to project slightly beyond the various plates 11.

Heretofore, racks have been provided with sliding supports but in the sliding structure it is necessary to slide the support out of position, load the same with rubber stock and then slide the same back into position. When using the stock, a reverse action is necessary, while in the present construction the respective supporting plates are dropped into position quickly and the rubber stock may be thrown into position easily. It will be seen from Figure 5 that the apertures 4 are offset from the plane of the plate 11. This is very desirable in that it will allow the various plates to be raised to an almost vertical position as shown in the upper part of Figure 2 and occupy a minimum space. The feet or legs 12 are beveled on one part whereby they permit the plates to be freely swung upwardly or downwardly. It will also be noted that the legs or feet are formed with an offset member 35 positioned to make it bear against the catch in a line parallel to the catch and indirectly make the frame bear against the catch in a line parallel to the catch. The catch is able to hold a substantial weight that is parallel to it but cannot hold a small weight that is pushing at an angle and, consequently, the member 35 is essential to the proper functioning of the catch to hold the plates in their raised position.

What I claim is:

1. A rubber stock rack, comprising a frame, a plurality of plates pivotally mounted in said frame, means for causing said plates to swing to almost a vertical position, and a vertically reciprocating rack for locking said plates in their elevated position, said rack being shiftable to allow one plate at a time to fall to a horizontal position.

2. A rubber stock rack, comprising a frame, a plurality of plates carried by the frame, means for swinging all of said plates to one side, said means including a vertically reciprocating rack and means for releasing said plates successively so that the said plates will move one at a time back to their former position, said releasing means includ-

ing a pivotally mounted catch positioned to be moved by said rack to an inoperative position as the rack is raised whereby said plates will be released and permitted to drop under 5 the action of gravity.

3. A rubber stock rack, comprising a frame, a plurality of spaced supporting plates carried by the frame, a manually actuated drum, a cable connected with said drum 10 and the lowermost plate, said connection being so positioned with regard to the pivotal mounting of the plates as to cause the plates to be swung upwardly when the cable is pulled by said drum, and catches 15 for supporting said plates in their raised position after said drum has been unwound, a weight acting on each catch for automatically holding the catch in an operative position, and a vertically reciprocating member 20 for shifting, one at a time, said catches to an inoperative position whereby said plates are permitted to fall one at a time back to their former position.

4. A rubber stock rack, comprising a frame, a plurality of pivotally mounted plates carried by the frame, means for swinging said plates to a raised position, a vertically movable rack for locking said plates in their raised position, and gear 30 mechanism for actuating said rack.

5. A rubber stock rack, comprising a frame, a plurality of pivotally mounted plates carried by the frame, means for swinging said plates on their pivotal mounting so that they will be in an almost vertical 35

position, a vertically movable rack for locking said plates in their raised position, means connected with said frame for guiding said rack in a vertical up and down movement, a gear meshing with said rack, and manually 40 actuated means for operating said gear whereby said rack may be gradually raised and thereby release said supporting plates individually.

6. In a rubber stock rack, a frame, a plurality of pivotally mounted plates carried by the frame, means for swinging said plates to an almost vertical position, pivotally mounted catches for locking the same in an almost vertical position, a vertically 45 movable rack for successively engaging and moving said catches to an inoperative position and said plates will swing downwardly to a horizontal position one at a time, a gear meshing with said rack, and manually 50 actuated means for actuating said gear for shifting said rack.

7. A device of the type described comprising a frame, racks carried by said frame, means for raising all of said racks, stops 55 carried by said frame and being positioned so as to support each rack in its raised position, common means for moving all of said stops into inoperative position to permit the racks to be raised, said means being adapted 60 to release any one or all of said stops consecutively so as to have the racks freed from said stops one at a time.
